UNITED STATES PATENT OFFICE.

LEONARD ROLL, OF WILKES-BARRE, PENNSYLVANIA.

DEVICE FOR CONTROLLING RUNAWAY HORSES.

SPECIFICATION forming part of Letters Patent No. 310,322, dated January 6, 1885.

Application filed September 26, 1884. (No model.)

To all whom it may concern:

Be it known that I, LEONARD ROLL, a citizen of the United States, residing at Wilkes-Barre, in the county of Luzerne and State of Pennsylvania, have invented a new and Improved Device for Controlling Runaway Horses, of which the following is a full, clear, and exact description, reference being had to the accompanying drawings, in which—

10 Figure 1 is the horse's head in perspective, having on a bridle to which the device is attached. Fig. 2 is a front view of a bridle with the device attached, and Fig. 3 is a side view of the same. Fig. 4 is a cross-section of the 15 device about full size. Fig. 5 is a side view, and Fig. 6 a front view, of the same.

The object of the invention is to provide 20 means to prevent horses from running away. I attain this object by the mechanism illustrated in the accompanying drawings.

To the front of the bridle, as shown in Figs. 1, 2, and 3, is fixed the device A, the construction of which is as follows: In the case B, Figs. 4, 5, and 6, is fitted a rod, C, Fig. 4, having on its lower end an eye, D, and a collar, e. Around the rod C is fixed a spiral expansion-spring, f, one end resting on the collar e and the other against a shoulder at g in the case B. To the eye D are attached the ends 25 of two cords or small chains, H, the other ends of which are attached to the blinds I of the bridle. On the upper end of the rod C is formed an eye, J, to which is attached a line, k, which is led back to the carriage or wagon, so as to be convenient to the hands of the 30 driver.

In driving, should the horse become frightened or otherwise unmanageable and attempt to run away, the driver takes hold of the line k and pulls on it, which, through the rod C 40 and the cords H, will cause the blinds I to close over the eyes of the horse, and prevent him from seeing, and thereby prevent him from running away. To uncover the eyes of the horse again it is only necessary to release 45 the tension on the line, and the spring f, pulling in the opposite direction, will cause the blinds to resume their normal position.

Having since the filing of this application 50 become aware of the existence of devices for preventing horses from running away prior to my invention thereto, I do not broadly claim such; but

What I claim, and desire to secure by Letters Patent, is—

1. In a device for controlling runaway horses, the combination of the case B with the rod C, the eye D, the collar e, the shoulder g, the spring f, the cords or chains H, and the eye J, to form the device A, all substantially as 60 described.

2. The combination, with a bridle, of the case B, the rod C, the eye D, the collar e, the spring f, the shoulder g, the cords or chains H, and line k, all substantially as described. 65

LEONARD ROLL.
